UNITED STATES PATENT OFFICE.

JOSEPH A. LACOURSE, OF MUSKEGON HEIGHTS, MICHIGAN.

CORE-WIRE-BENDING MACHINE.

1,299,583.

Specification of Letters Patent.

Patented Apr. 8, 1919.

Application filed May 10, 1918. Serial No. 233,664.

To all whom it may concern:

Be it known that I, JOSEPH A. LACOURSE, a citizen of the United States of America, residing at Muskegon Heights, in the county 5 of Muskegon and State of Michigan, have invented certain new and useful Improvements in Core-Wire-Bending Machines; and I do hereby declare the following to be a full, clear, and exact description of the invention, such as will enable others skilled 10 in the art to which it appertains to make and use the same.

The present invention relates to a wire bending machine and one which is particularly 15 adapted for bending lengths of wire into various shapes for use in reinforcing and strengthening sand cores used in the operation of molding. Many different shapes and varieties of wire forms are needed 20 to strengthen and reinforce different shapes and forms of sand cores, and it is an object and purpose of my invention to provide a machine with several adjustable parts which may be fixed in different positions 25 with respect to each other and the remainder of the machine, whereby a great variety of wire forms may be readily made with a single machine. Another object and purpose of the invention is to make a machine 30 in which a plurality of wires may be bent at one and the same time into a desired shape on the machine. Still further objects and purposes of the invention are the production of a machine of this character 35 of a relatively simple construction, one which may be very readily operated when once set for a certain form to bend a large number of wires in a short time, and one which may be adjusted to bend other forms 40 of wires in a very easy and simple manner. All of these features, together with many others not specifically enumerated at this point, will appear as understanding of the invention is had from the accompanying 45 drawing, in which,

Figure 1 is a front elevation, partly in section, of the wire bending machine.

Figs. 2 and 3 are elevations, respectively, of opposite ends of the machine.

Figs. 4 and 5 are plan and front elevations, respectively, of an element of the machine which will appear more fully hereafter, and

Figs. 6 to 11 inclusive represent a few of 55 the many different wire forms which may be bent on the machine.

Like reference characters refer to like parts in the different views of the drawing.

In construction a supporting base 1 is provided from which, at spaced apart intervals, 60 uprights 2 extend, each having a bearing 3 at its upper end to support a shaft 4, the same extending at each end a distance beyond the bearings. A hand wheel 5 is connected to the shaft between its ends for turning the same and, if desired, a handle 6 may be used as a substitute for the wheel, the wheel, however, being a preferred construction. Stop pins 7 are mounted on the uprights 2 and collars 8 are connected to 70 the shaft 4 adjacent each end of the uprights, from each of which an arm 9 extends, the same being adapted to strike against the pins 7 to limit the rotation of the shaft in either direction. The collars 8 75 may be adjusted to different positions on the shaft being held thereon by set screws so as to vary the rotative movement of the shaft.

At each end of the shaft a member 10 is 80 adjustably secured being held thereon by setscrews, the same being formed into a disk-like head 11 in the face of which a T-shaped slot 12 is cut. The head 11 is of circular outline and in the periphery thereof of a plurality of screw-threaded holes 13 are 85 made. The slot 12 is adapted to receive a plurality of different devices such as cylinders 14, pins 15, or cam-like members 16, as shown in Figs. 2 and 3, which may be located at various positions in the lengths 90 of the slots 12 being held in any position to which they are adjusted in any suitable manner. Also a bar 17 may be connected to a head 11 and extend therefrom as shown, 95 a suitable attaching screw passing through the bar and threading into any opening 13 previously described.

At the corners of the base 1, brackets 18 and 18^a are secured on which slotted posts 19 are pivotally mounted. I have shown the 100 pivotal mounting of the posts 19 to brackets 18 at a point below the supporting base 1. The pivotal connection of the posts 19 to the brackets 18^a is above the base 1. I prefer that the pivotal connection be below the 105 base to give greater rigidity to the construction, but it is to be understood that the structure is operable in either case. Each bracket 18 and 18^a has an arc-shaped slot 20 cut therein through which a bolt 21 mounted 110 on the associated post 19 extends, the same being adapted to receive a nut to bind the

post 19 in any position to which it may be moved with respect to the bracket.

Various types of members may be adjustably mounted on the posts 19. For instance, 5 I have shown a member 22 connected to certain of the posts, the same having a connecting stud 22^a passing through the slot in the post whereby said member may not only be adjusted lengthwise of the post, but have 10 a limited pivotal movement with respect thereto. A pin and slot connection illustrated at 23 serves to hold the member 22 in any position to which it may be pivotally adjusted. Arms 24 extend from the member 15 22 between which a grooved roller 25 is rotatably mounted. The arms 24 extend toward the head 11 but in a plane a slight distance beyond said head and, as shown in Figs. 2 and 3, the member 22 carrying 20 said arms 24 may be inverted if desired in certain instances.

Another member 26 may be mounted on one of the posts 19, being pivotally and adjustably mounted thereon by use of attaching 25 screws 26^a and the pin and slot connection illustrated at 27. An arm 28 extends from the member 26 turning upwardly at its end and being formed with a series of notches 29.

30 With a member 22 as described connected to one post 19 at one end of the machine, and a member 26 connected to the post 19 at the opposite side, and with a cylinder 14 and a pin 15 fixed in the slot 12 of the head 11, 35 as shown in Fig. 2, a plurality of wires 30 may be passed over the roller 25 between the cylinder 14 and pin 15 and over the notched end 29 of the arm 28, it being apparent that the wires lie side by side being received in 40 the notches 29 and in the grooves of the roller 25. Then by turning the shaft 4 a partial rotation, these wires may be bent into the form shown at 30^a in Fig. 11. It is obvious that by changing the position of the 45 various members 22, 26, 14, 15, and 17, or by substituting a different member, such as 16, for the cylinder 14, or by changing the position of the collars 8 so as to change the amount of rotation of the shaft 4, an almost 50 endless variety of forms may be made with this set up of the machine.

I have also shown a slotted link member 31 adjustably connected by a bolt 32 to one of the posts 19, the same carrying at its 55 inner end a sheet metal member 33. With the set up shown in Fig. 3, a plurality of wires 34 may be bent into the shape illustrated at 34^a in Fig. 10. Not only may the wires be passed above the member 33, but the 60 same may be passed through between the members 16 and the pin 15 so as to strike against the member 33, whereupon a different shape or form of wire will be produced. In addition, the pivotal connection of the 65 posts 19 to their supporting brackets 18 or

18^a permits a wide variety in forms to be made. In fact with this machine the number of wire forms which can be produced is practically unlimited, and substantially every type of reinforcing wire for sand cores can 70 be made on a single machine.

From the foregoing, it will be apparent that I have produced a relatively simple but very practical and efficient wire bending machine which may be used to bend many different kinds of wire forms particularly adapted for strengthening and reinforcing sand cores. Of course the machine is not limited to the one use. Various changes in detail of structure may be resorted to without departing from the invention and I, accordingly, do not wish to be limited to the exact structure shown and described, but consider myself entitled to all modifications of structure which fall within the scope of 85 the appended claims defining the invention.

I claim:

1. A wire bending machine comprising a support, a shaft rotatably mounted on and above the support, means for limiting the 90 extent of rotation of the shaft, two posts mounted on the support adjacent an end and one at each side of the shaft, means mounted on said end of the shaft, and separate coöperating means adjustably mounted for movements lengthwise of each post for receiving wires and bending the same on rotation of 95 the shaft.

2. A wire bending machine comprising a support, a shaft rotatably mounted on and 100 above the support, means adjustably mounted on the shaft, and coöperating means on the support for limiting the extent of rotation of the shaft, said amount of rotation of the shaft varying with different adjustments 105 of said means thereon, two posts mounted on the support adjacent an end and one at each side of the shaft, means adjustably mounted on said end of the shaft, and coöperating means adjustably mounted on each 110 of the posts for receiving wires and bending the same on rotation of the shaft.

3. A wire bending machine comprising a support, a shaft rotatably mounted on and above the support, means for limiting the 115 extent of rotative movement of the shaft, a post pivotally mounted on the support adjacent an end and at each side of the shaft, said posts being movable toward or away from the shaft, means for fixing said posts 120 in any position to which they are moved, means adjustably mounted on the end of the shaft, and coöperating means adjustably mounted on each post for receiving wires and bending the same on rotation of the 125 shaft.

4. A wire bending machine comprising a support, a shaft rotatably mounted on and above the support, means for limiting the extent of rotative movement of the shaft, a 130

post mounted adjacent an end of the shaft and at each side thereof, a head on said end of the shaft, devices adjustably mounted on and projecting from the head, and coöperating devices mounted on the posts and extending toward the head for receiving wires and bending the same on rotation of the shaft.

5. A wire bending machine comprising a support, a shaft rotatably mounted thereon, 10 means for limiting the extent of rotative movement of the shaft, a post mounted adjacent an end and at each side of the shaft, a head on said end of the shaft, devices adjustably mounted on the head, a member mounted for adjustment lengthwise of each post, and other members pivotally mounted on each of the first mentioned members and extending toward the shaft, said devices on the head and said other members coöperating to 15 receive wires and bend the same on rotation 20 of the shaft, substantially as described.

6. In a wire bending machine, a support, a shaft rotatably mounted a distance above the support, means for manually turning the shaft, means for limiting the extent of rotation of the shaft, a head, having a slot in its face, connected to an end of the shaft, devices adjustably mounted in said slot and projecting from the head, a post mounted at each side of and adjacent the head, a member pivotally and slidably mounted on each post, means to secure said members in any desired position on the posts, and an arm extending from each member toward the head, wires being adapted to be operatively received between said arms and in association with said devices on the head, and bend on rotation of the shaft and attached head, substantially as described. 25 30 35

In testimony whereof I affix my signature. 40

JOSEPH A. LACOURSE.
